CLAIM

The ornamental design for a leather fabric sheet for bags, as shown and described.

DESCRIPTION

The patent or application file contains at least one drawing executed in color. Copies of this patent or patent application publication with color drawing(s) will be provided by the Office upon request and payment of the necessary fee.

1. Leather fabric sheet for bags

The sole FIGURE is a front view of a leather fabric sheet for bags showing my new design.

The dash-dash broken lines around the figure depict the boundaries of the claim and form no part thereof. The broken lines within the boundaries depict stitching which is a feature of the claimed design.
